J. S. MERENNA

METHOD AND MEANS FOR MANUFACTURING AND REPAIRING SHIRTS

Filed Oct. 30, 1924

UNITED STATES PATENT OFFICE.

JOHN S. MERENNA, OF BROOKLYN, NEW YORK, ASSIGNOR OF ONE-TENTH TO HERBERT B. MOSES, OF WASHINGTON, DISTRICT OF COLUMBIA.

METHOD AND MEANS FOR MANUFACTURING AND REPAIRING SHIRTS.

Application filed October 30, 1924. Serial No. 746,768.

My invention relates to a method of repairing worn or torn shirts as well as to an improved neckband for carrying out said method.

- 5 It is a well known fact that men's shirts in a large number of instances, first show signs of wear in the front, adjacent the neckband, due to rubbing of the collar, and to the strains occasioned by ironing them.
- 10 This rubbing produces a hole in the bosom of the shirt anywhere between the front collar button and the seam securing the yoke to the bosom of the shirt. It has heretofore become necessary for the wearer to
- 15 have the shirt repaired with a patch which is unsightly, or to discard the shirt.

An object of my invention is to repair the shirt in a neat and sightly manner, and the means therefor, and I have devised an improved neckband by the use of which the shirt may be fixed so it can be worn, without it showing any indication of having been repaired.

The invention comprises a combination of parts and steps in the method.

Referring to the accompanying drawings: Fig. 1 is a perspective view of a portion of a shirt with one of my improved neckbands thereon in the position it occupies when the shirt is first made;

Fig. 2 is a similar view showing the neckband in the position after the shirt is repaired;

Fig. 3 is a sectional view on the line 3—35 of Fig. 1;

Fig. 4 is a view showing one form of the front portions of the neckband; and

Fig. 5 is a view showing a modified form.

The bosom 1 of the shirt is sewed to the 40 yoke 2 at the seam 3, the yoke extending across the back and over the shoulders, and has the back 4 of the shirt secured to it at the seam 5, and the yoke is made of one or more plies of material, according to the 45 quality of the shirt; all as is usually done in the manufacture of shirts.

My improved neckband is made of a plurality of sections, preferably three (3), sewed together. For example, the section

6 comprises the greater part of the neckband 50 to form the back thereof, and is sewed to the yoke 2 throughout its length, its ends being on a line with the seams 3. It is preferably made of four plies of material, although this number may be varied as desired, and the plies are stitched together along their upper and lower edges, except that at a point midway between the ends the lower stitching securing the two outer plies to the inner plies is omitted to permit of insertion of a collar button, and the outer plies at this point are formed with the back button hole 7 in the usual manner. At the 55 ends, the inner plies are cut short of the outer plies forming a pocket 8, the lines of stitching along the edges defining the upper and lower edges of the pocket, the extreme outer and inner plies forming the walls thereof.

The front sections 10 of the neckband are also preferably, but not necessarily, made of four plies of material stitched along their edges, and at their meeting ends they are provided with buttonholes 11 in the usual manner. At their other ends, the inner plies extend beyond the outer plies to form the tongues 9, and thus each tongue is an integral part of each of the sections 10 of the neckband.

If desired, the tongues and pockets may 80 be reversed.

It will be clear that the tongues being of a two-ply thickness, and the pockets being equal to two plies of thickness, the tongues can readily be secured in the pockets without causing any undue thickness at this point, in the case of four-ply bands, which would be uncomfortable to the wearer of the shirt.

Other provision can be made for the pockets and tongues, but I prefer that above described. For example, alternate plies may be cut short to provide pockets or the equivalents thereof on one section of the neckband, while other alternate plies may be cut 85 short on the other section thereof to provide alternate tongues corresponding to the pockets or the equivalents thereof on the

first mentioned section. In fact, any desired method of forming the pockets and tongues may be used.

The tongues are tapered and are of some-
5 what less width than the pockets, which
pockets are substantially the width of the
neckband, so that each tongue before it is
stitched in the pocket can have a certain
10 amount of vertical movement therein, for
a purpose which will be hereinafter ex-
plained.

If desired, a strip or yoke piece 12 may
be formed as part of each section 10 and
extend outwardly toward the sleeve, under
15 the yoke, the stitching of seam 3 securing
the strip to the yoke. This strip serves to
reinforce the yoke at the shoulder, when the
latter is made of one ply of fabric, but when
20 made of more than one ply, the strip may be
dispensed with, if desired.

If, after continued use, a short bosom be-
comes worn adjacent the neckband, the sec-
tions 10 are ripped off and a strip is then cut
off the upper edge of the bosom, on a line 15
25 with the lower edge of the worn portion.
The same sections 10, or other sections 10 of
the required shape, are then sewed onto the
shirt bosom, and the tongues 9 being of less
30 height than the pocket and tapered, allow
the members to be swung down to the low-
ered upper edge of the bosom. The tongue
is, of course, sewed into the pocket, as it was
before. This results in the holes for the
35 front collar button being slightly lower than
they were originally, but when the shirt is
again worn, the neckband will adjust itself
to the neck of the wearer. This will raise the
front of the neckband to the original pos-
40 sition, causing a slight pull on the front of the
shirt, but it will not be enough to cause any
bulging or discomfort to the wearer. The
uppermost button 17 of the shirt, the button-
hole 18 corresponding thereto, as well as the
45 other buttons and buttonholes of the shirt,
may be so adjusted with relation to their dis-
tance from the neckband that the raising of
the bosom on making the repair will not
cause the buttons to assume an unsightly or
50 uncomfortable position.

The sections 10 may be made of several
different shapes, according to requirements.
In the form shown in Fig. 4 the end having
the buttonhole is curved upwardly; while
55 in the form shown in Fig. 5, an enlargement
13 protrudes from the lower edge to take
care of an unusually large hole in the position
shown.

It is also possible to make the sections
60 forming the neckband of different lengths to
take care of holes worn through the yoke
back of where sections 10 join sections 6 of
the neckband. When this happens, the en-
tire neckband may be removed and a new
65 back member, shorter than the original one,
secured to the shirt. The torn part of the

yoke is then cut away and new front mem-
bers longer than the original ones are sewed
in place.

It is within the scope of my invention to
use other shapes of neckbands than those
70 herein disclosed, particularly in Figs. 4
and 5 of the drawings, the exact shape of the
neckband sections depending upon the posi-
tion of the line along which the shirt is to be
cut when making the repair. However, a
75 great many different shapes are not essential,
a small number which can be carried in stock
being sufficient for ordinary repair work.

What I desire to secure by Letters Patent
of the United States and what I claim is:

1. A shirt having a neckband consisting
of sections sewed together and to the shirt,
the connection between the sections being by
means of pockets and tongues in the pockets,
85 the number of plies at the joint being the
same as in the body part of the neckband.

2. The method of repairing worn or torn
shirts consisting of removing the front sec-
tions of a neckband made of several parts,
cutting away the bosom of the shirt adjac-
90 ent the neckband, and securing in place
neckband sections shaped to accommodate
the cutaway part of the bosom.

3. The herein described method of repairing
95 worn or torn shirts having a sectional
neckband which consists in removing the
front sections of the neckband, cutting away
the bosom part of the shirt to eliminate the
worn or torn part thereof, and securing
100 properly shaped front sections of the neck-
band to the back section thereof and to the
bosom.

4. As an article of manufacture a neck
band consisting of sections and adapted to
105 be sewed to a shirt, the connection between
the sections being by means of pockets and
tongues in the pockets, the number of plies
of the joint being the same as in the body
part of the neck band.

5. A replacing front neckband section for
shirts designed to replace a front replaceable
section in a sectional neckband, said replace-
able section having means to secure the same
110 to a back neckband section and having a
button hole adapted to register with a sec-
ond button hole in the shirt neckband, said
replacing front section having means ar-
ranged for attachment to the back section
corresponding to the securing means of said
front replaceable section and having a but-
ton hole registerable with said second but-
ton hole, said replacing section having a pro-
jection at the lower edge adapted to register
115 lower on the shirt than the replaceable sec-
tion when said replacing section is attached
and aligned.

6. A replacing front neckband section for
shirts designed to replace a front replaceable
section in a sectional shirt neckband, said re-
placeable section having means to secure the
120

same to a back neckband section and having a button hole adapted to register with a second button hole in the shirt neckband, said replacing front section having means arranged for attachment to the back section corresponding to the securing means of said front replaceable section and having a button hole registerable with said second button hole, said replacing section having a projection at a portion only of the lower edge adapted to register lower on the shirt than the replaceable section when said replacing section is attached and aligned.

JOHN S. MERENNA.
